UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

MANUFACTURE OF BOOTS AND SHOES.

1,082,621.

Specification of Letters Patent. Patented Dec. 30, 1913.

Application filed October 5, 1910, Serial No. 585,432. Renewed October 17, 1913. Serial No. 795,791.

To all whom it may concern:

Be it known that I, MATTHIAS BROCK, a citizen of the United States, residing at Boston, in the county of Suffolk and State 5 of Massachusetts, have invented certain Improvements in the Manufacture of Boots and Shoes, of which the following description, in connection with the accompanying drawings, is a specification, like reference 10 characters on the drawings indicating like parts in the several figures.

This invention relates to the manufacture of shoes and particularly to a novel method of making shoes and it has for its object to 15 improve the fitting of the shoe at the sides of the shoe, more especially at the front portions of the heel and the rear of the shank. A usual practice is to last this portion of the shoe by means of shear-like wipers having 20 shaped edges to embrace the heel portion of the shoe and be closed over the heel bottom to rub the upper inwardly upon the bottom face of the shoe to position to be secured to the innersole. It is found that with the lasts 25 now in use, in which the last bottom is comparatively narrow at the breast of the heel and at the shank, insufficient upper tightening force is applied by the wipers at the 30 portions of the shoe acted upon by their ends. In accordance with this invention additional upper tightening force is obtained without the employment of any supplementary mechanism. I make use of a known 35 construction of heel stiffener which has an upstanding lip on each wing provided to stand against the outer face of the innersole lip. I shape this lipped stiffener so that its lips stand in the assembled shoe more or less away from the innersole lips and I employ 40 the stiffener lips as an abutment or backing against which the upper is gripped by an edge face of the wipers, or, it may be, of any other lasting plate than the wiper which 45 acts on the rear portion of the heel. By so gripping the upper between the two opposed faces each of which can move in the direction of the force applied, the upper is pulled as distinguished from being wiped or rubbed 50 inwardly from the last edge to tighten it. I 55 may employ lasting plates the upper gripping edges of which are serrated or provided with pointed projections the better to engage the upper with a non-slipping grip against the stiffener lip while the latter serves as an abutment or coöperating grip-

ping member. In accordance with a further step in this novel method I bend the upper over the top edge of the stiffener lip and grip it upon said edge as well as gripping it against the outer side of this lip. 60 The stiffener is made of hard slightly resilient material and is usually compressed in its manufacture. The upstanding edge is usually skived to render it thin before the stiffener is molded so that said edge presents a 65 narrow, sharp face by which the upper bent over it is held to a substantial extent. By bending the upper over this edge, then downwardly against the side face of the lip and then outwardly over the flange of the 70 stiffener the upper is held thereto with a friction that insures a strong tightening pull as the stiffener and upper are forced inwardly by the lasting plate. The lasting plate may be provided for the above stated 75 purpose, with an inwardly directed ledge or overhanging fin spaced above its lower face a distance about equal to the height of the stiffener lip and adapted to bend the upper over and grip it down upon the top edge 80 of said lip as the serrated face approaches and grips the upper against the outer face of said lip.

The invention will now be explained in connection with the accompanying drawings 85 which illustrate the described method and also an apparatus, including a novel construction of wipers or lasting plates, which may be employed in practising this invention, although it will be understood that the 90 novel method is not dependent upon any particular apparatus with which to practise it.

In the claims at the end of the description the novel method will be particularly 95 pointed out as also the new features of the wipers.

Figure 1 is a plan view of the rear portion of a shoe in the process of lasting; Fig. 2 is a perspective sectional view; Fig. 3 is 100 a similar view in which an upper holding clamp is being used; Fig. 4 is a perspective view from below of the novel wiper of Figs. 1 and 2.

The innersole 2, the upper 4 and the heel 105 stiffener are assembled upon the last in the usual manner. The stiffener has the flange 6 which at the forward portion of each wing is narrowed by turning up a lip 8. The flange is skived to present a sharp edge on 110

the upstanding lip 8 and the stiffener which is formed of hard sole leather, or some material having similar characteristics, is molded to the illustrated shape which is substantially permanent although the stiffener is more or less resilient and is usually moistened before the lasting operation so that it will take the shape to which it is compressed in that operation and will set in that shape as the shoe dries. The stiffener will be shaped in accordance with this invention so that the lips 8 will stand laterally away from the lips 10 of the innersole in the assembled shoe as in Fig. 3. The heel embracing wipers 14, which are advanced and closed to force the upper and the stiffener flange inwardly upon the innersole to position to be fastened, have their inner edges outwardly offset at 15, near the location of the breast line of the heel, and the continuation thereof at 16 extends along the side of the shoe toward the end of the stiffener wing. The edge 16 may be serrated or provided with pointed projections 18 and this edge and its projections may be overhung by a ledge or fin 20 the lower face of which is spaced above the lower face of the wiper a distance substantially equal to or slightly less than the height of the lip 8 on the stiffener. In use the ledge 20 bends the upper over and clamps it down upon the sharp top edge of the lip 8, Fig. 2, and the side of said lip forms an abutment or backing for the upper while the advancing edge 16, with its serrations 18, grips the upper against the outer face of said lip. As the wiper continues its closing movement it springs the wings of the stiffener inwardly and said lips and the edges 16 coöperate to pull the upper inwardly in addition to and as distinguished from the mere wiping or rubbing action of the wiper over the stock. In the finished work the heel portion of the shoe hugs the heel of the wearer's foot better and has less tendency to slip up and down, especially in oxfords and pumps, because of this formation of the heel stiffener. The work performed by the parts 16, 18 and 20 might obviously be performed by hand or by plates 50 separate from the wipers.

It will be noted that the end portions of the wipers have a substantial component of forward movement toward the toe of the last as they close over the shoe bottom and that, 55 inasmuch as the serrated faces 16 grip the upper in a manner to restrain slipping, the upper at the sides of the heel and shank will be pulled forwardly as well as inwardly. It is important to emphasize the essential distinction between the pulling action effected by gripping the upper against the lip 8 and forcing the upper and the lip inwardly together and the well known wiping action effected when the wiper rubs frictionally 60 over the upper. It is because the latter

action is insufficient that the former is provided in accordance with this invention. The apparatus herein disclosed presents an invention which is to be protected as well as the method, the claims on the apparatus being found in a divisional application Serial No. 655,912, filed October 21, 1911. For further assisting the wiper to tighten the upper over the last at the end of the heel stiffener the wiper may have the clamp 25, 70 Fig. 3. This clamp is pivoted to the wiper and acted upon by a bow spring 26 to force it down upon the upper with a sufficient gripping force. The connection between the spring and the clamp is above the pivot of the clamp when the clamp is down and below the pivot when the clamp is up so that the spring holds the clamp in its upraised position as well as in its downturned position. The clamp has a handle 28 by which 80 to operate it and this handle is arranged to afford means by which the operator may apply additional force with his hand to grip the upper more securely on one side of the shoe or the other in a special case requiring 85 particular attention.

Having explained the nature of this invention and described how the novel method may be practised, I claim and desire to secure protection for all the patentable novelty 90 herein disclosed and the following claiming clauses are to be construed broadly to give effect to this intention:

1. That improvement in methods of making welt shoes which consists in assembling 100 upon a last and an innersole upper materials which include a heel stiffener formed with wings each of which is provided with an inturned flange and with an upstanding lip located at the inner edge of the flange, 105 gripping the upper against said upstanding lip of the heel stiffener at each side of the heel, and forcing the gripped upper and the stiffener wings inwardly together to tighten the upper over the last.

2. That improvement in methods of making welt shoes which consists in assembling upon a last and an innersole upper materials which include a heel stiffener formed with wings each of which is provided with 115 an inturned flange and with an upstanding lip located at the inner edge of the flange, wiping the upper over the bottom face of the heel end of the last, and gripping the upper between the wiping means and said 120 upstanding lip of the heel stiffener at each side of the heel during the overworking operation to increase the tightening pull upon the upper near the end portions of the stiffener.

3. That improvement in methods of making welt shoes which consists in assembling upon a last and innersole upper materials which include a resilient heel stiffener provided with wings and an upstanding lip or 130

rib at the end of each wing and so formed that said lips normally stand outwardly away from the lips of the innersole, gripping the upper against said stiffener lips 5 and forcing the stiffener lips inwardly with the upper held thereagainst to pull the upper while carrying it and said lips inwardly to position to be secured to the innersole lips.

10 4. That improvement in methods of making welt shoes which consists in forming a heel stiffener with wings having upstanding lips located to stand against the outer faces of the innersole lips, assembling the shoe, 15 wiping the flange of the stiffener and the upper inwardly over the heel seat and gripping the upper between said upstanding lips and the edge of the wiping means to exert pulling force upon the upper at the 20 front of the heel in addition to the wiping operation.

5. That improvement in methods of making shoes which consists in forming a heel stiffener with wings that spread at their 25 upper edges to a greater width than they are to have in the lasted shoe and with an upstanding lip on each wing, assembling upon a last the heel stiffener so formed, together with an inner sole and an upper, 30 gripping the upper against said lips, and forcing the upper and the wings inwardly together to exert a positive pull upon the upper, as distinguished from a mere wiping effect, to tighten the upper over the last.

35 6. That improvement in methods of making shoes which consists in forming a heel stiffener with wings that spread to a greater width than they are to have in the lasted shoe and with an upstanding lip on each

wing, fixedly engaging the upper and forcing it against said lips, and then crowding said lips and the upper inwardly by said engaging means to exert a positive pull, as distinguished from a mere wiping effect, to tighten the upper at the sides of the shoe. 40 45

7. That improvement in methods of making shoes which consists in forming a heel stiffener with resilient wings that spread to a greater width than they are to have in the lasted shoe and with an upstanding lip 50 on each wing, assembling upon a last the heel stiffener so formed, together with an inner sole and an upper, gripping the upper against the top edges and the outer faces of said lips as abutments, and springing the 55 stiffener wings into lasted position while the upper is so gripped to pull the upper over the last, as distinguished from merely wiping the upper into lasted position.

8. That improvement in methods of making shoes which consists in assembling upon a last an inner sole, an upper, and a heel stiffener having wings formed with upstanding portions, wiping the upper over the edges of the heel stiffener, fixedly engaging 60 the upper with the upstanding portions of the heel stiffener wings, and forcing said upper and wings inwardly by a direct pull in addition to the wiping effect, to tighten 65 the upper at the sides of the shoe. 70

In testimony whereof I have signed my name to this specification in the presence of two subscribing witnesses.
